UNITED STATES PATENT OFFICE.

HAMMOND CHARLES HASTINGS, OF RUGBY, ENGLAND, ASSIGNOR TO GENERAL ELECTRIC COMPANY, A CORPORATION OF NEW YORK.

ELECTROMAGNETIC SWITCH.

1,331,063.

Specification of Letters Patent. Patented Feb. 17, 1920.

Application filed July 8, 1919. Serial No. 309,300.

To all whom it may concern:

Be it known that I, HAMMOND CHARLES HASTINGS, a subject of Great Britain, residing at Rugby, in the county of Warwickshire, England, have invented certain new and useful Improvements in Electromagnetic Switches, of which the following is a specification.

My invention relates to electromagnetic switches for controlling electric circuits and more particularly to switches of the lock-out type, which hold open when the current in a circuit is relatively high and close when the current drops to a predetermined value.

In the starting of electric motors, it has been the practice to employ a plurality of electromagnetic switches which close successively to cut out sections of resistance from the motor circuit and bring the motor up to speed. Various means have been devised for controlling the operation of the switches so that they will only close when the current is at a proper value, that is, after a switch has operated to cut out a section of resistance the next switch will not operate until the current has dropped to a safe value due to the speeding up of the motor.

A form of switch which has frequently been proposed for this purpose is one in which a shunt coil closes the switch and a series coil, instead of controlling the circuit of the shunt coil, positively prevents the switch from closing by actually holding it open, that is, the shunt coil pulls against the series or "holding-out" coil. The difficulty with this type of switch is that the value of current in the holding-out winding at which the switch will close depends upon the pull of the shunt coil, which of course will vary with the voltage and also with the temperature of the coil. In other words, the "setting" of the switch, *i. e.*, the motor current value at which it closes, changes with change of voltage. It also closes at one value of current in the series coil when the shunt coil is cold and another when it is at its operating temperature which is ordinarily about 60 degrees C.

The object of the present invention is to obtain a lock-out magnet having a shunt closing coil and series lock-out coil in which the balance between the closing and holding open forces will not be affected by the variations in line volts and resistance of shunt closing coil referred to above, and which

will be free from the disadvantages inherent to the use of a common magnetic circuit for the series lock-out coil flux and the lock-out component of the shunt coil flux.

Referring to the drawings, Figure 1 is a plan view of a contactor embodying my invention; Figs. 2 and 3 are respectively left and right hand elevations of the same; and Fig. 4 is a diagram for explaining the principle of my invention.

The contactor consists of a shunt closing coil 10, with its magnet core 11, yoke 12, and armature 13 which is pivoted at 14; a lock-out magnet having coil 16 and core 17 and a compensating magnet having shunt coil 18 and core 19. Coil 18 is connected in series with the shunt closing coil 10, and is used for neutralizing the effect of the variations in pull of the shunt closing magnet. The magnetic circuits of the three magnets are independent of each other. The lever 13 which forms the armature for the closing coil is shown having a projection 15 which forms the armature for the magnets 16 and 18, but three separate armatures could be used, provided that they were rigidly fixed together.

In Fig. 1 the contactor is shown in the open position, the lever 13 resting against the stop 20 which is made of non-magnetic material. 26 is a base of insulating material, 23 and 24 contacts for carrying the main current, and 25 a spring for producing wiping action between the contacts in a manner well known in the art. It will be seen that the pulls due to the compensating magnet 18 and lock-out magnet 16, are both opposed to the closing magnet 10. The only forces acting on the moving arm of the contactor when in the open position are those due to gravity, lock-out magnet and compensating magnet tending to lock open, and the force due to the shunt coil 10 tending to close the contactor. No springs are used. The compensating and lock-out magnets are both fitted with adjustable air gaps, so that the magnetic circuit of either can be altered without affecting the magnetic circuit of the shunt closing coil. The compensating magnet circuit is adjusted in the first place to give the necessary compensating effect by means of the adjustable iron cap 22, which is then permanently locked in position on the core 19. As the coil 18 of this magnet is in series with the shunt closing coil 10,

the same changes in current, due to heating and voltage variation, occur in both coils. The magnet circuit of 18 is proportioned so that any change in the pull of the closing magnet is balanced by a corresponding change of the pull due to 18, over the working range of the contactor. The cap 22 enables small adjustments to be made to compensate for variations in manufacture. The 10 adjustable iron cap 21 of the series lock-out magnet is used for adjusting the reluctance of the magnetic path of this magnet, so that the lever 15 will be released and contactor close when the current in its coil 16 has 15 dropped to the desired value.

The principle on which the contactor operates is illustrated in Fig. 4. Curve OCA shows the relation between the force in the moving arm produced by the closing coil 20 and the current in the coil, and curve OFE the corresponding pull of the compensating magnet, assuming that this operates at the same leverage as the closing coil. Both are shown on the same side of the horizontal axis, although one is opposed to the other. OB= current corresponding to maximum line volts when coil is cold. OD= current corresponding to minimum line volts when coil is at its maximum temperature. 30 AG= change in the pull of the closing coil due to maximum variation in temperature and line volts. AE= closing force opposed to gravity and the series lock-out coil when shunt coil current is OB. CF= closing force 35 opposed to gravity and the series lock-out coil when shunt coil current is OD.

If for all points such as K between D and B the corresponding closing force HJ opposed to gravity and the series lock-out coil 40 is such that $HJ = AE = CF$ exact compensation is produced and the resultant closing force opposed to gravity and the series lock-out coil will be constant for all variations of current in the closing coil for the working 45 range of the contactor. This is the result which is required so that when the lock-out magnet is set to release at a particular value of the current, it will do so, although the current in the closing coil may have any 50 value between OD and OB.

The advantages of my contactor over those previously devised will be readily understood from the following:—If the magnetic circuit of the lock-out magnet were not 55 independent of the magnetic circuit of the closing coil, the release current adjustment could not be made as described above, as altering the reluctance of the series lock-out magnet would at the same time affect the 60 closing circuit and would therefore not produce the desired effect. If as an alternative the adjustment is not made by altering the magnetic path, but by altering the tension of a spring applied so as to oppose the force 65 of the lock-out magnet—the arrangement

being such that the lock-out magnet has to attract its armature to it through an air gap—there is a possibility of the contactor closing while the current in the series coil is higher than the desired value. The reason 70 for this is that with such an arrangement a higher value of current is required in the series coil to attract the armature through the air gap, than to retain it in a position closer to the coil. For the same reason, such 75 an arrangement cannot be set so that a minimum lock-out value of the current is as close to the corresponding maximum value of the series current at which the contactor will close, as the contactor we have described in 80 which the armature of the lock-out magnet when in the open position is brought by gravity to the position where it is retained by the lock-out magnet.

In accordance with the provisions of the 85 patent statutes, I have described the principle of operation of my invention, together with the apparatus which I now consider to represent the best embodiment thereof, but I desire to have it understood that the apparatus shown is only illustrative and that 90 the invention can be carried out by other means.

What I claim as new and desire to secure by Letters Patent of the United States, is:— 95

1. An electromagnetic switch comprising a switch member, an electromagnet for actuating the same, an electromagnet for opposing the movement of said switch member, an electromagnet energized responsively to the 100 energization of the actuating electromagnet and assisting the opposing electromagnet for compensating for variations in the actuating force due to the variations in the current in the actuating coil so that the switch member 105 will be actuated when the current in the opposing magnet drops to a predetermined value.

2. An electromagnetic switch of the lock-out type having a shunt wound closing magnet, a series lockout magnet the flux path of which is independent of that of the closing magnet, and a shunt wound compensating magnet the coil of which is in series with the closing coil and the pull of which assists the 110 lock-out magnet, so that variations in pull of the closing magnet due to voltage and temperature variations are balanced by corresponding variations in the pull of the compensating magnet. 115

3. An electromagnetic switch having a single movable pivoted switch lever, a shunt wound closing magnet for actuating the switch, a series lock-out magnet and a shunt wound compensating magnet the coil of 120 which is in series with the closing coil and the pull of which assists the lock-out magnet, the flux paths of the series lock-out magnet and the shunt wound compensating magnet being independent of each other and inde- 125 130

- pendent of that of the closing magnet, whereby variations in the closing force due to variations in the current in the shunt wound closing magnet are balanced by corresponding variations in the pull of the compensating magnet so that the switch will be actuated when the current in the opposing magnet drops to a predetermined value. 4. An electromagnet switch having a single movable pivoted switch lever, a shunt wound closing magnet on one side of the fulcrum of said lever, a series lock-out magnet and a shunt wound compensating magnet the coil of which is in series with the closing coil and the pull of which assists the lock-out magnet, on the other side of the fulcrum of said lever, the flux paths of the series lock-
- out magnet and the shunt wound compensating magnet being independent of each other and independent of that of the closing magnet, whereby variations in the closing force due to variations in the current in the shunt wound closing magnet are balanced by corresponding variations in the pull of the compensating magnet so that the switch will be actuated when the current in the opposing magnet drops to a predetermined value. 20 25

In witness whereof, I have hereunto set my hand this 13th day of June 1919.

HAMMOND CHARLES HASTINGS.
